RATCHET-TYPE FLOOR LAYING TOOL

William A. Miller, near Weston, Colo.

Application June 29, 1953, Serial No. 364,657

2 Claims. (Cl. 254—14)

As a development from and an improvement over the disclosures of my United States Patent No. 2,588,401, dated March 11, 1952, and my pending application for United States patent Serial No. 316,925, now Patent No. 2,710,166, filed October 25, 1952, this invention relates to floor-laying tools and has as an object to provide an improved construction and operative interrelation of elements constituting such a tool.

A further object of the invention is to provide an improved floor-laying tool employable to crowd matched flooring boards into intimate edge contact and to hold said boards in such crowded relation during the nailing thereof, the tool being operable to establish and to hold successive slight increments of board shift throughout an extensive range.

A further object of the invention is to provide an improved floor-laying tool characterized by a multiple ratchet latch operable to retain the ram element of the tool in the various practical positions of its adjustment.

A further object of the invention is to provide an improved floor-laying tool conveniently and efficiently operable to establish and maintain board crowding pressures of a high order at the precise points where such pressures are needful.

A further object of the invention is to provide an improved floor-laying tool adapted for convenient and ready release from its various operative dispositions.

A further object of the invention is to provide an improved floor-laying tool operable in association with a complementary adjunct to accomplish its purposes closely adjacent any wall limiting the area of a floor.

A further object of the invention is to provide the combination with a floor-laying tool of an adapter employable to condition the tool for operation closely adjacent a wall limiting the area of a floor.

A further object of the invention is to provide an improved adapter cooperable with a floor-laying tool to condition said tool for practical use closely adjacent a wall limiting the area of a floor.

A further object of the invention is to provide an improved tool and adapter of the character and for the purposes hereinafter described that is simple and inexpensive of production, facile of use, adaptable to effective operation in a variety of particular situations, positive and efficient in attainment of the ends for which designed, and durable throughout a long period of repetitious use.

With the foregoing and other objects in view, my invention consists in the construction, arrangement, and operative combination of elements as hereinafter set forth, pointed out in my claims, and illustrated by the accompanying drawings, in which—

Figure 1 is a side elevation of a preferred embodiment of the improved tool, as assembled and positioned ready for practical use.

Figure 2 is a top plan view of the organization according to Figure 1.

Figure 3 is a vertical section longitudinally through the

2

illustrated embodiment of the improvement taken substantially on the indicated line 3—3 of Figure 2.

Figure 4 is a vertical section taken transversely of the illustrated organization substantially on the indicated line 5 4—4 of Figure 3.

Figure 5 is a fragmentary, detail enlargement of the ratchet arrangement illustrated in Figure 3.

Figure 6 is a side elevation of an adapter cooperable with the tool shown in the preceding views to condition 10 said tool for accomplishment of its purposes closely adjacent a wall, the position of the ratchet tool being indicated by broken lines.

Figure 7 is a top plan view of the adapter shown in Figure 6 as separated from the ratchet tool.

Figure 8 is an end elevation of the adapter shown in Figure 7.

The purpose, utility, and general operative principle of the present improvement hereinabove noted; it being common knowledge that matched floor boards, such as tongue-and-groove, require to be crowded and pressed into intimate engagement of their matched edges during laying of a floor to attain desired high quality of result. In a structural departure from the disclosures of my patent and pending application, the instant invention provides a tool 25 effective to accomplish all of the functions inherent in my earlier disclosures with facility and advantage, and to accomplish certain other functions for which the earlier tools were not equally well adapted.

All of the elements of the improved tool with the exception of an adapter, later to be described, are assembled in an operative unit on or in supported relation with a preferably-rectangular base 10 of suitable rigid material, such as metal. The base 10 is formed as an integral unit, preferably by casting or molding, in any appropriate size 30 characterized by a length greater than its width and a thickness adequate for accommodation of associated elements, as will hereinafter appear. For convenient reference, the end of the base 10 remote from the floor boards acted upon by the tool during the use thereof is identified by the numeral 11 and is considered to be the rear end of the assembly, while the opposite end of said base, designated by the numeral 12, is considered to be and is termed the front end of the unit.

The under side of the base 10 is centrally and longitudinally routed to provide a channel opening through the under face of said base and through the base front end 12, but not through the base rear end 11, to form a slideway for a straight, elongated ram member 13. The ram member 13 is expediently rectangular in transverse section to engage within and to fill the correspondingly-rectangular slideway of the base 10, thus to inhibit any tendency of the ram member to rotate in its mounting, said member is of a length to extend longitudinally of the base 10 and beyond the base front end 12 when the opposite end of the member is seated against the inner face of the closed base rear end 11, and a plate 14 is detachably engaged with the under face of the base 10 in bridgeing relation across the slideway occupied by the member 13 to retain the latter in said slideway for reciprocation longitudinally of the base; said plate 14 preferably extending from the base front end 12 beneath and along the major length of the member 13. The end portion of the member 13 projecting beyond the base 10 when said member is fully seated in its slideway is 55 worked to the form of a cylindrical boss 15 loosely receivable in a cylindrical socket formed centrally in and to open through the rear face of a presser block 16 having a length approximating the width of the base 10, whereby to mount said block 16 on, in advance of, and for travel 60 with the exposed end of the member 13 in a manner permitting said block to rock slightly on and adjust relative to the boss 15 terminating said member. The block

65 70 75 80 85 90 95

16 is formed with a forwardly-directed face parallel to the base front end 12 and with a groove 17 longitudinally of said face in position to embrace and accommodate the conventional edge tongue of a flooring board, as will hereinafter more fully appear.

The long sides of the base 10 are longitudinally undercut, or rabbetted, to receive and seat spur plates 18 detachably engaged with said sides of the base, as by means of cap screws 19, said plates 18 extending in width beyond the under face of the base 10 and being formed with spurs 20 in spaced succession along their free margins and in an inclination convergent toward the plane of the base rear end 11; it being the function of said spurs 20 to bite into a sub-floor and thereby anchor the base to the floor in any desired position of use.

Appropriately spaced inwardly of the base rear end 11, paired ears 21 integrally upstand from the upper surface of the base 10 at opposite sides of the base longitudinal median line and in alignment transversely of said base, and an elongated slot 22 longitudinally intersects the base thickness adjacent the outer side of each ear 21 and extends in both directions beyond the adjacent ear. The ears 21 are apertured to receive a pin 23 thereby mounted to bridge between said ears transversely of, above, and parallel to the base 10 upper face, and ends of said pin extending beyond the ears 21 engage with the spaced, parallel, like, arms 24 of a rigid, U-shaped yoke 25 thereby pivotally mounted for actuation through a vertical arc. The arms 24 of the yoke 25 are entered through and accommodated for oscillation in the slots 22 intersecting the base 10, the base member of said yoke 25 spans in clearing relation across the ears 21, and a manipulating finger 26, expediently in the form of an open loop, is fixed at one end to and centrally of the yoke base member in extension thence toward the base rear end 11; said arms 24 and finger 26 being so angularly related as to dispose the arms at a downward inclination toward the base front end 12 with the arm tips at approximately the plane of the base under surface when said finger 26 is engaged with the base upper surface, as shown in Figure 1, whereby elevation of the finger 26 operates to rock the yoke 25 about its pivotal mounting and to engage the free ends of the arms 24 with the sub-floor supporting the assembly for retraction of the spurs 20 from their penetration within said sub-floor. From the position of the slots 22, the base 10 is longitudinally routed through its under face to provide channels opening through the base front end 12 wherein are loosely accommodated retractile coil springs 27 resiliently intercoupling the yoke arms 24 and corresponding ends of the presser block 16, said springs functioning in an obvious manner to yieldably hold the yoke 25 with its finger 26 engaging the upper surface of the base 10 and to yieldably retain the presser block 16 on and for limited adjustment about its mounting boss 15; such spring coupling of the block 16 to other elements of the assembly facilitating interchange of particular blocks 16 when and as desired.

As is manifest, the springs 27 operate by virtue of their retractile character to hold the member 13 at the inner limit of its range of reciprocation relative to the base 10, in which position the block 16 is disposed parallel to and closely adjacent the base front end 12 with the block groove 17 directed away from the assembly, in which relation of elements the unit is positioned for use with the length of the base 10 perpendicular to the edge of a flooring board which is to be crowded into place and with the groove 17 positioned to receive the tongue element of said board edge, and the spurs 20 are engaged with the sub-floor to secure the unit in such disposition, whereafter extension of the ram member 13 from the base operates to crowd the floor board away from the base 10 and against the adjacent, previously placed flooring board.

A significant feature of the improvement is the arrangement and organization of ratchet means manually operable to extend the ram member 13 from the base 10

and to latch said member in any of various minor increments of its extension. Longitudinally and centrally of the base 10 upper surface and inwardly adjacent the base front end 12, an opening through said base upper surface between ears 28 fixedly upstanding from and in alignment transversely of said base exposes a length of the member 13 top surface, which latter surface is transversely and uniformly toothed, as at 29, throughout the major length thereof. Hinged on a pin 30 carried by the ears 28 transversely of, above, and parallel to the base top surface an end-opening clevis 31 is mounted with its open yoke directed toward the member 13 and with its axially-socketed other end directed away from the base 10 for the reception of an actuating lever 32, of appropriate length, removably and replaceably associated therewith. A pin 33 carried by the arms of the clevis 31 and bridging the yoke of said clevis parallel to the pin 30 pivotally mounts a ratchet detent 34 engageable with the teeth 29 of the member 13, and a tapered lug 35 outstands from the detent 34 radially of the pin 33 under the yoke base of the clevis 31 and toward the base rear end 11 in such manner as to slidably engage a beveled base margin 35' at the rear end of the opening wherein the detent operates as the lever 32 approaches the limit of its swing toward the base front end 12 and thereby rock the said detent 34 on its mounting pin 33; such engagement of the lug 35 with the margin 35' functioning to lift and hold the detent 34 out of coaction with the teeth 29 of the ram member 13 at each forward limit of lever 32 oscillation and consequently releasing said ram member to the influence of the springs 27 as modified by the latches hereinafter described each time the lever with its attachments is set for a ram-extending stroke. Forwardly of the base 10 from and parallel to the pin 30, a pin 36 bridges between web extensions of the ears 28 to pivotally mount a bank of similar latch fingers 37 disposed to incline downwardly and toward the base front end 12 to engagement of their lower ends with the teeth 29 of the member 13. The latch fingers 37 are alike save as to their length extension between the mounting pin 36 and their free ends engageable with the teeth 29, each of said fingers being formed with an eccentric curved nose 38 rearwardly of and above the pin 36 and with a free end 39 shaped for coaction with the teeth 29, and a plurality of such fingers 37 is mounted in parallel adjacency on the pin 36 to provide a bank coextensive in width with the toothed upper surface of the member 13 so arranged as to permit individual oscillation of said fingers on the said pin. At the base front end 12, a clamp plate 40 detachably engaged transversely of the base secures a comb-like leaf spring 41 in position to bear against and to apply pressure to the forwardly-exposed upper margins of the fingers 37, one of the spring 41 teeth bearing separately against each of the fingers 37, thereby to hold the free ends 39 of said fingers into ratcheting engagement with the teeth 29 of the member 13 while permitting independent oscillation of the fingers 37 against the so-imposed pressure of the spring 41. Since the latch fingers 37 have their free ends 39 at varying distances from the pin 36, it is clear that one of said fingers, at least, will latch with a tooth 29 at each slight outward shift of the member 13, even though the member shift be much less than the distance between adjacent teeth 29, thus assuring retention of the member 13 in every position of slight adjustment outwardly of the base 10. Release of the fingers 37 from latching relation with the teeth 39 is manually accomplished, when desired, by means of a yoke 42 hinged by its arms to the pin 36 and bridging at its base across and closely adjacent upper arcs of the fingers 37, which yoke is furnished with a manipulating finger 43 outstanding centrally from its base. As should be apparent, rocking of the yoke 42 on its mounting pin 36 in an arc toward the base rear end 11 serves to engage the yoke base with the eccentric nose arcs 38 75 of all of the fingers 37, thereby rocking said fingers simul-

taneously against the pressure of the spring 41 and raising the finger free ends 39 into clearing relation with the teeth 29; release of the yoke permitting the spring 41 to return said fingers 37 into coacting relation with said teeth 29.

Constructed and assembled as illustrated and hereinabove described, the tool is completely ready for practical use. The free end of the lever 32 being moved to the limit of its travel toward the base front end 12, the point of the lug 35 is trapped under the margin 35' to hold the detent 34 out of coaction with the teeth 29 of the ram member 13, and a rearward rocking of the yoke 42 by means of its finger 43 lifts the latches 37 out of engagement with said teeth to fully free the ram member for retraction within the base by means of the springs 27. With the ram member fully retracted, the springs 27 yieldably maintain such ram disposition and simultaneously hold the tips of the yoke arms 24 retracted within the base 10, while release of the yoke 42 permits the spring 41 to return the latches 37 into ratcheting engagement of their free ends with the ram teeth 29. Conditioned as set forth, the tool is positioned on a sub-floor relative to the matched boards of the finish floor as above set forth and the lever 32 is oscillated to actuate the tool for its intended purposes. As the lever 32 is swung toward the base rear end 11, the lug 35 is cleared from under the margin 35' to permit engagement of the detent 34 with the teeth 29, whereafter the lever travel operates through the clevis 31 and said detent to feed the ram member 31 outwardly of the base against the tension of the springs 27, the free ends of the latches 37 ratcheting successively over the apex of each tooth 29 passed thereunder to retain the successive increments of ram extension. At the limit of its ram-extending stroke, or at any point in such stroke, the lever 32 is reversely oscillated to freely ratchet the detent 34 over the teeth 29 and to a new purchase thereon effective for progressive extension of the ram, the latches 37 securely holding the extended ram against retraction during such lever manipulation. With the spurs 20 caught in the sub-floor and the head 16 engaged with the floor board to be crowded, extension of the ram member 13 accomplished as above set forth is applied to most effectively engage the crowded board in intimate edge contact with the board previously laid and to hold the crowded board while it is securely nailed. Having accomplished its function in a given setting, the tool is quickly conditioned for reuse in a new location by swinging the lever to the limit of its forward travel for release of the detent 34 from the teeth 29, rocking of the yoke 42 against the pressure of the spring 41 to lift the latches away from the teeth 29 and thereby permit retraction of the ram member within the base, and lifting of the finger 26 to rock the arms 24 into engagement of their tips against the sub-floor with a leverage effective to release the spurs 20, thus fully resetting and freeing the tool for immediate reuse.

As is obvious, the tool as shown and described is available for effective practical use throughout all of a given floor area except a strip paralleling the length of the boards being laid and extending outwardly from a wall toward which the floor is closing a distance equalling or exceeding the overall length of the tool, within which strip it is manifest that the tool may not function in its usual manner. Corrective of this minor, but important, inadequacy of the tool, it is expedient to provide an adapter of the type illustrated in Figures 6, 7 and 8 wherethrough the operative characteristics of the tool may be applied to flooring boards filling the gap above mentioned.

The adapter consists of a rigid, unitary frame fabricated in any expedient manner to receive and mount the base 10 of the tool in the manner hereinafter set forth. The adapter frame is rectangular in plan and is characterized by parallel, vertical flanges 44 spaced apart to receive the width of the base 10 therebetween, by a vertical end flange 45 closing between corresponding ends of the

flanges 44 and determining the length of the latter as approximately equal to the length of the base 10, by horizontal flanges 46 extending in coplanar relation inwardly from the lower margins of the flanges 44 and 45 to stiffen the assembly and to provide strips against which the spurs 20 of the tool may rest, and by a member 47 fixedly bridging between the ends of the flanges 44 remote from the flange 45 beneath or in the plane of the associated elements 46 and characterized by a depending flange 47' spacedly paralleling the flange 45 in a vertical extension opposite to that of said latter flange. The adapter frame is designed to rest upon the finish floor with its length perpendicular to the boards thereof and with its flange 47' depending across the unfinished edge of the finish floor and into marginal engagement with the sub-floor, in which disposition the adapter receives the tool assembly as shown by broken lines in Figure 6, the spurs 20 of the tool resting upon the longitudinally-disposed flanges 46, the rear end 11 of the tool base abutting the flange 45, and the head 16 of the tool being directed for projection through the open end of the frame above the element 47, in which relation of elements the tool may be operated with the head 16 against a wall to develop pressures tending to shift the adapter and its tool on the finish floor and away from the wall. To apply the pressures effective to shift the adapter on the finish floor for crowding of successive floor boards into place, a rigid, U-shaped yoke 48 is formed with a base adapted to bridge transversely under the adapter frame and with parallel legs arranged to stand across the exterior faces of the spaced flanges 44, and sockets 49 for the reception of the legs of the yoke 48 are fixed to and outstand from the flange 44 exterior faces in a spacing along said flanges 44 approximating the usual width of a flooring board and in such registration transversely of the adapter as will dispose the yoke engaged therein with its base parallel to the flanges 45 and 47'. One side face of the yoke 48 base is longitudinally slotted, as at 50, for coaction with the tongue member of a flooring board, and with the yoke 48 assembled to the adapter in the manner illustrated, the slot 50 of the yoke base is opposed to the free edge of a flooring board being laid and operates to crowd the board away from the wall and into place as the tool is operated in the adapter to shift the assembly away from the wall. The yoke 48 is engaged with the appropriate pair of sockets 49 and the tool is operated as above set forth until the last width of flooring is to be laid, at which time the yoke is removed and the flange 47' is utilized to complete the crowding of the last board strip. Manifestly, any desired number of paired sockets 49 may be supplied on a given adapter frame in any preferred spacing longitudinally of the frame, thus expediently conditioning the adapter for use with flooring boards of varying widths.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

60 I claim as my invention:

1. In a floor-laying tool having a base provided with means for penetrative engagement with a sub-floor, a ram reciprocable longitudinally and through one end of said base, and means manually actuatable to extend said ram from the base, a presser block loosely and telescopically engaged with and projecting laterally at each side of the exposed ram end exteriorly of the base, a yoke hinged to and adjacent the end of the base remote from said presser block to dispose the yoke arms at a downward and inward inclination through the base and toward said presser block, and a retractile coil spring longitudinally and loosely traversing the base at each side of said ram in engagement between the arm of the yoke and the lateral projection of the presser block at the same side of the ram, whereby said springs function

to yieldably retract the yoke arms within the base, to retain the presser block in mounted relation with the exterior end of the ram, and to urge said ram inwardly of the base.

2. In a floor-laying tool having a base provided with means for penetrative engagement with a sub-floor, a ram reciprocable longitudinally and through one end of said base, and means manually actuatable to extend said ram from the base, a presser block loosely and telescopically engaged with and projecting laterally at each side of the exposed ram end exteriorly of the base, a channel longitudinally of the base at each side of the ram opening through the lower surface of the base and the end thereof intersected by the ram, a yoke hinged to and adjacent the end of the base remote from said presser block to dispose the yoke arms at a downward and inward inclination toward the presser block through the base and the inner ends of said channels, and a retractile coil spring longitudinally of and loosely within

each of said channels in engagement between the arm of the yoke and the lateral projection of the presser block at the same side of the ram, whereby said springs function to yieldably retract the yoke arms within the base, to retain the presser block in mounted relation with the exterior end of the ram, and to urge said ram inwardly of the base.
